Joseph A. Bruce

(57) **CLAIM**

The ornamental design for a barbecue grill, as shown and described.

DESCRIPTION

FIG. 1 is a front perspective view for a barbecue grill showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a front perspective view with the lids in a closed or folded position thereof in use.

The broken lines in the drawings depict portions of the barbecue grill that form no part of the claimed design.

1 Claim, 8 Drawing Sheets
